UNITED STATES PATENT OFFICE.

ADOLF ROM, OF LIAN, NEAR CHRISTIANIA, NORWAY.

RAIL-CLEANER.

SPECIFICATION forming part of Letters Patent No. 689,024, dated December 17, 1901.

Application filed October 10, 1900. Serial No. 32,652. (No model.)

To all whom it may concern:

Be it known that I, ADOLF ROM, a subject of the King of Sweden and Norway, residing at Lian, near Christiania, Norway, have invented certain new and useful Improvements in Rail-Cleaners; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has for its object a device which is designed to be mounted on tram-cars or locomotives for the purpose of cleaning the rails of dirt, snow, or other obstacles lying on or beside the same. Peculiar to this rail-cleaner is that the scrapers are mounted upon a rotatable block or support so as to yield or turn rearwardly when striking upon a fixed obstacle, thereby causing the support to revolve and place another scraper in position upon the rails.

25 In the accompanying drawings, Figure 1 is a side elevation, and Fig. 2 a plan, partly in section, of a rail-cleaner for tram-cars embodying the present invention.

30 *a a'* is a frame which is pivotally secured at *u* to the frame or any other part of the car and supported by means of a chain *b* or any other suitable means. The two parts *a* and *a'* of the frame are hinged together at *h*, so that the lower part *a* is capable of swinging laterally relatively to the upper one, *a'*. Because of the springs *i* this lower part *a* of the frame will constantly tend to keep an intermediate position. Pivotally mounted on a pin *c* at the rear end of the frame is a square 35 head *d*, serving as support for the scrapers.

40 A spring *f*, acting against one of the lateral faces of the head, serves to hold the same in position. When the scraper in operation strikes upon a fixed hindrance—for instance, a projecting rail end—the spring *f* will yield and allow the head to turn ninety degrees, so as to place the next scraper in operative 45 position upon the rail. The head *d* is laterally movable upon the pin *c*, so as to be capable of yielding a little in the lateral direction, being held in an intermediate position by the action of the spring *g*. A

greater lateral play is secured by the hinge-joint *h*, which might of course afford alone the required lateral play; but I find it preferable to provide for a double mobility, the sliding head providing for the smaller and the hinge-joint *h* for the greater movements. 55

My new rail-cleaner is well fitted for use, both on tramways and on railways, for sweeping the rails or scraping off snow or ice along the same.

I claim—

1. A track-cleaner comprising a two-part frame connected to turn on a vertical pivot, 65 one of said frame parts adapted to be pivotally connected to a car and the other carrying a revoluble scraper, and a resilient connection between the frame parts operating to return them into a normal position when 70 moved out of it by the turning of one of the frame parts on the aforesaid vertical pivot, for the purpose set forth.

2. A track-cleaner comprising a scraper-carrier adapted to be pivotally connected to 75 a car, a scraper mounted to revolve in bearings in said carrier having teeth arranged at angles of ninety degrees, and a spring adapted to act on bearing-faces of the scraper to antagonize its rotation and hold one of the 80 teeth thereof in operative position, for the purpose set forth.

3. A track-cleaner, comprising a scraper-carrier adapted to be pivotally connected to a car, a scraper mounted to revolve and slide 85 laterally on a pin having its bearings in the carrier, said scraper having its teeth arranged at angles of ninety degrees and provided with four corresponding bearing-faces and springs exerting power on one of the faces of and on 90 the end of said scraper respectively, for the purpose set forth.

4. A track-cleaner, comprising a two-part frame *a*, *a'* connected to revolve on a vertical pivot *h*, part *a'* adapted to be pivotally connected to a car, the squared scraper-carrier *d*, having a scraper *e* secured to each of its faces, said carrier of greater length than the width of the scrapers *e*, and having also motion lengthwise on its support, springs connecting the frame parts and antagonizing their rotation in either direction on the aforesaid vertical pivot, and springs acting on one of the faces of the extension of the scraper-car- 100

rier and on one end thereof respectively, for the purposes set forth.

5. A track-cleaner, comprising a scraper-carrier adapted to be pivotally connected with a ear, a scraper revolvably mounted on the carrier and consisting of a square head having scrapers secured to its faces and a spring acting on the faces of the head to antagonize

its rotation and hold a scraper in operative position, for the purpose set forth.

In witness whereof I have hereunto set my hand in presence of two witnesses.

ADOLF ROM.
